ABSTRACT

A metering and dispensing apparatus with a pump having intake and discharge strokes coupled to a switching valve which cylindrically connects the pump in open communication with a first, then a second, port with an idling pause between the conditions. A mechanism converting rotary motion to sinusoidal reciprocating motion actuates the pump piston, the length of stroke of the piston being selectively adjustable within the motion conversion mechanism in accordance with an indicator indicative of the desired volume.

METERING AND DISPENSING APPARATUS

This application is a continuation-in-part of application Ser. No. 812,177, filed Apr. 1, 1969, now U.S. Letters Pat. No. 3,669,319.

This invention relates to a metering cum dispensing apparatus of the kind for repeatedly drawing off, through a conduit, a volumetrically metered, freely adjustable, quantity of liquid and for discharging this metered quantity through another conduit, each drawing off operation alternating with a discharging operation.

Metering cum dispensing apparatuses of this kind are known: they are mainly used in test laboratories, e.g. biochemical and clinical laboratories, and are intended either to deliver a predetermined volume of a liquid to be analyzed (i.e. operating as a metering apparatus), or to deliver successively several metered quantities, all of identical volume, of the same liquid (i.e. operating as a dispensing apparatus), or else to deliver simultaneously both a volumetrically predetermined metered quantity of a liquid having to be analyzed and a metered quantity, also volumetrically predetermined but not necessarily of same volume as the liquid to be analysed, of a diluting liquid or of a reagent (i.e. operating as a diluting apparatus). The use of these apparatuses is becoming more and more widespread as the demand for chain testing increases. However, the known apparatuses are often of low accuracy, inasmuch as the volumetric quantities they meter lack accuracy and are not readily reproducible, particularly when these volumetric quantities are small.

This defect is largely due to the fact that, in these known forms of apparatus, adjustment of the metered quantity is not "digitalized." Indeed, adjustment is, as it were, continuous and such adjustment is often affected by errors in the reading of scales, these being human errors attributable to distraction, inattention or tiredness on the part of the operators. Moreover, the known forms of metering apparatus operate in a rather brutal way. First, an abrupt suction action occurs, then an abrupt stoppage of the suction action and finally an abrupt discharge of the metered quantity of liquid that has been sucked in. This often results in cavitation or breaks in the columns of liquid (hydraulic hammering effects) or in the formation of drops, both being a source of material errors. If it is desired to reduce the extent of these errors, this can only be achieved, with these known forms of metering cum dispensing apparatus, by having them handle relatively large quantities of liquid. This of course is a major drawback when it is required to carry out a large number of different tests on a liquid from one source since, in order to do this, a corresponding number of samples is usually required of the liquid and this means that quite a sizable starting quantity will be needed. The only way in which this need for a sizable starting quantity of the liquid can be avoided is to reduce to the greatest possible extent the volume of each sample. Hence, the desirability of minimizing all possible causes for inaccuracy in metering. This is particularly important in haematology where it is often desired to carry out a large number of tests without having to draw off large quantities of blood from the patients. One of the most relevant examples is in pediatric haematology.

An object of the present invention is to overcome the above mentioned drawbacks by providing a metering cum dispensing apparatus which is able to meter with

great accuracy very small volumes of liquid and which will lend itself, because of the reproducibility of the metered quantities it delivers, to an automation of testing.

5 It is a further object of this invention to provide a metering and dispensing apparatus having two piston pumps with selectively variable strokes in order to meter and/or dispense any predetermined volume of liquid.

10 A further object of this invention is to provide a novel valve switching mechanism for a metering and dispensing apparatus.

A further object of this invention is to provide various novel improved metering and dispensing pumps.

15 Still another object of this invention is to provide an improved variable stroke motion for a metering and dispensing apparatus.

According to the present invention there is provided apparatus of the kind set forth which comprises

20 a. a unit having

1. a suction and forcing piston pump able, during a suction stroke, to draw off said predetermined volume,

2. a switching valve associated with said pump and able cyclically to pass from one condition in which it causes said pump to communicate with one of said conduits, to a second condition in which it causes said pump to communicate with the other of said conduits,

25 3. a drive mechanism able to cause said valve to pass from one condition to the other and able cyclically to actuate said pump by imparting to the reciprocating movement of the piston a substantially sinusoidal action, said mechanism being adapted so that the suction strokes of the pump occur when the valve is in said one condition and that the forcing strokes of the pump occur when the valve is in said other condition and so that each suction and forcing stroke may be followed by an idling pause during which the valve passes from one condition to another,

30 4. adjustment means for selectively adjusting the volume of said metered quantity by varying the length of the stroke of the pump piston, and

35 5. display means for displaying to the outside a number indicative of said volume;

40 b. an electric motor coupled to the drive mechanism of said unit; and

45 c. control means for controlling said electric motor and adapted to trigger off at will half an operational cycle of said unit, said half cycle being either a drawing off half cycle, including a suction stroke of the pump, or a discharge half cycle, including a forcing stroke of the pump.

50 Three embodiments of the apparatus provided by the invention will now be described by way of example with reference to the accompanying drawings, in which:

55 FIG. 1 is a side view, in cross-section of a first embodiment of this invention;

FIG. 2 is a front sectional view of the first embodiment, taken along line II-II of FIG. 1;

FIG. 3 is a rear sectional view of the first embodiment, taken along line III-III of FIG. 1;

FIG. 4 is a plan view of the first embodiment;

FIG. 5 is a front elevational view of the first embodiment;

FIGS. 6 and 7 are detail sectional views taken along lines VI-VI and VII-VII, respectively, of FIG. 1, on a somewhat enlarged scale;

FIG. 8 illustrates a further detail, partly in section, of

the first embodiment on a substantially enlarged scale; FIG. 9 shows three graphs illustrating the operation of the first embodiment;

FIG. 10 shows a portion of FIG. 1 on a substantially enlarged scale and in more detail;

FIG. 11 shows the electrical wiring for the first embodiment;

FIG. 12 is a side view, in cross-section, of the second embodiment;

FIG. 13 is a front sectional view of the second embodiment, taken along line XIII—XIII of FIG. 12;

FIG. 14 is a rear sectional view of the second embodiment taken along line XIV—XIV of FIG. 12;

FIG. 15 is a top sectional view of the second embodiment taken along line XV—XV of FIG. 12;

FIG. 16 is a front elevational view of the second embodiment;

FIGS. 17 and 18 are detail sectional views taken along lines XVII—XVII and XVIII—XVIII respectively, of FIG. 12;

FIG. 19 shows three graphs illustrating the operation of the second embodiment;

FIG. 20 shows on a substantially enlarged scale and in a more detailed manner a portion of FIG. 12;

FIG. 21 is a side view of a third embodiment of the invention, showing the stroke length adjustment mechanism in section;

FIG. 22 is a plan view of the third embodiment of FIG. 21;

FIG. 23 is an enlarged sectional view of the stroke adjustment mechanism shown in FIG. 21;

FIG. 24 is a perspective view of the stroke adjustment mechanism of FIG. 23;

FIG. 25 is an exploded view of the crank arm and slide block arrangement of the stroke adjustment mechanism;

FIG. 26 is an exploded view of the pump valve actuating mechanism;

FIG. 27 is a side sectional view of the pump and valve switching mechanism of the third embodiment of this invention;

FIG. 27a is a perspective view of the valve actuating member of the third embodiment;

FIG. 28 is a front view of the pump and switching mechanism in FIG. 27;

FIG. 29 is a sectional view taken along line 29—29 of FIG. 27;

FIG. 30 is a sectional view taken along line 30—30 of FIG. 27; and

FIGS. 31-34 are diagrammatic views of the various modes of operation of the present invention.

The metering cum dispensing apparatus shown in FIGS. 1 to 5 is dual, inasmuch as it comprises a pair of suction and forcing pumps 1a and 1b, a pair of switching valves 2a and 2b, a pair of drive means 3a and 3b (powered however by a single common motor 4 through a single common speed-reducing gear), a pair of adjustment means 6a and 6b, a pair of display means 7a and 7b, but a single control means comprising an electric automatically cutting out contact-maker 8 and an electric camactuated contact-breaker 9. Of each of the dual members only one need be described, the components of each such member being identified by three-figure reference numerals so chosen that their first figure corresponds to the reference numeral of the member to which they belong. Thus, all of the components forming part of the pump in the first two embodiments whether it be pump 1a or pump 1b, will be identified by numerals ranging from 101 to 199, all those forming part of the valve, whether it be valve 2a or valve 2b, will be identified by numerals ranging from 201 to 299, and so forth. In view of the constructional symmetry of the dual members, the letter symbol that distinguishes one member from the other within a pair will be omitted. In the third embodiment, the pump is identified by numerals 500-599, the stroke adjustment mechanism by numerals 400-499, the valve actuating mechanism by numerals 800-899 and the remaining assembly by numerals 900-999.

FIRST EMBODIMENT-PUMP

15 In the present embodiment, the suction and forcing pump consists of a syringe 101 in which can move a piston 102 having a cap 103 and mounted at the end of a rod 104. Cylinder 101 is closed off by a plug 105 formed at its top end with a nipple 106 by means of which it communicates with the switching valve. Cylinder 101 is preferably made of glass, piston 102 and rod 104 are preferably made of metal, cap 103 and plug 105 are preferably made of hard synthetic material, such as Teflon (Registered Trademark for polytetrafluoroethylene) or Kel-F (Registered Trademark for fluorochloroethylene); but other materials may be used. The syringe is kept in place by an L-shaped element 107 which, in conjunction with a spring blade 108, holds it tight against the switching valve, with the nipple 106 of its plug 105 engaged in a recess formed for that purpose in the valve. As for the rod 104, it extends through a slot 109 formed in the short arm of the L-shaped element 107 and its free end portion is connected to the free end portion of a lever 339 forming part of the driven means.

FIRST EMBODIMENT-SWITCHING VALVE

The switching valve comprises a stationary body 201 which is fitted into a stationary socket 202, and a rotary valve member 203 which is fitted into a rotary socket 204. The valve body and the valve member are held together by an assembly sleeve 205 which fits into an opening 206 formed in a front wall 10 of the apparatus frame.

45 The valve is kept in place in this opening by a releasable holding device which consists of a plate 207 and of two knurled-headed tightening screws threaded into holes formed in the front wall 10 of the apparatus frame. When in position, the valve fits, by means of two holes formed in the base of the rotary socket 204, onto two driving pins 302 and 303 which form part of the drive means and which will be further described below. In this way, the valve member 203 can, as it were, be plugged on to the latter. Because of its design and of its manner of attachment, the switching valve can be exchanged as a unit, with the valve member and the valve body remaining connected together by means of the assembly sleeve 205, and such changes are exceedingly easy to perform, this being an advantage for servicing.

55 The valve body 201 is formed (see FIG. 6) with an axial passage 210 which communicates with a recess 211 into which is inserted the nipple 106 of pump 1 and with two lateral passages 212 and 213 which communicate with recesses 214 and 215 adapted to receive, respectively, one end of a flexible suction tube 11 and one end of a flexible discharge tube 12. The suction tube 11 communicates with an outside reservoir (not

shown) from which the apparatus is required to draw off metered quantities of a liquid contained therein; the discharge tube 12 communicates with an outside receptacle (not shown) to which these metered quantities are to be discharged or with a nozzle 31 fitted to a handle 30 enabling the metered quantities being discharged to be delivered at a desired location.

The valve member 203 is formed, in its face adjacent valve body 201, with a channel 216 having the approximate shape of an anchor (see FIG. 7), which, depending on the angular position of the valve member, causes the axial passage 210 in body 201 to communicate with either one or the other of the two lateral passages 212 and 213 in the body. Thus, upon rotation of the valve member 203 in relation to the stationary valve body 201, the pump successively comes to communicate with the suction tube and with the discharge tube. Such communication lasts for as long as it takes the arcuate portion 217 of channel 216 to sweep past the orifice of one or other of the lateral passages 212 and 213, which length of time is dependent, for a given speed, on the length (in degrees) of the arcuate portion 217. The length of portion 217 is of course less than 180° to avoid the possibility of direct communication between these two lateral passages.

FIRST EMBODIMENT-DRIVE MEANS

As mentioned earlier, the drive means are powered by one motor through a common speed-reducing gear. The motor, identified as 4, is preferably synchronous and the speed-reducing gear, identified as 5, comprises an output shaft 13 which carries a pinion 14. Pinion 14 is coupled to shaft 13 through the intermediary of a frictional torque-limiting device 15 (see FIG. 8) and meshes with the first wheel of each of the two drive means 3a and 3b. Although only drive means 3a will be described, it will of course be understood that what is about to be said in connection with drive means 3a is also true of drive means 3b since these are identical to 3a. Pinion 14 thus meshes with a cogged wheel 301 which carries the two pins 302 and 303 mentioned earlier. The latter extend through a flanged disc 304 and project, as already stated, into recesses formed in the base of the rotary socket 204 holding the rotary valve member 203 of the switching valve. Disc 304 forms, in conjunction with a spring 305, a resilient axial abutment which presses, through opening 206 and inside sleeve 205, the valve member 203 against the valve body 201. Wheel 301 drives a cogged wheel 306 secured to the input shaft 321 of an eccentric 320. Along two portions of the periphery of cogged wheel 301, the teeth have their axial length reduced by about half by means of milled arcuate recesses 307 and 307'. The axial length of the teeth on the cogged wheel 306 is less than the depth of the recesses 307 and 307' (see FIGS. 1 and 2). Moreover, wheel 306 is located in the plane of these recesses. Consequently, wheel 301 only drives wheel 306 during those portions of its rotation which coincide with the action of the non-recessed portions 308 and 308' of its periphery. Wheel 306 is mounted on a hub 309 which carries a radial spoke 310 spaced from wheel 306 and dimensioned to cooperate alternately with two pins 311 and 311' projecting from the side of wheel 301. Spoke 310 and pins 311 and 311' are so positioned that, upon engagement, they cause the teeth of wheels 301 and 306 to mesh as the front end of one or other of the non-recessed portions 308 and 308' is

about to come into engagement with the wheel 306. The peripheral length of the non-recessed portions 308 and 308' is equal to half the circumference of wheel 306 so that for each half turn of the wheel 301, wheel 306 carries out one half turn followed by a pause corresponding to the passage of one or other of the recessed portions 307 and 307'. The wheels 301 and 306 thus together form an intermittent drive able to convert the continuous rotation of wheel 301 into an intermittent rotary motion on the part of wheel 306 while leaving the latter free to rotate when either of the recessed portions 307 and 307' lies opposite thereto.

The eccentric 320 comprises a first rotary member 322 which is secured to the input shaft 321 and which is formed with a diametral slot 323 in which can slide axially an eccentricity setting member consisting of a blade 324 whose edges 325 and 326 are oblique in relation to the rotational axis 327 of the rotary member 322. The latter is positioned opposite a second rotary member 328 which is also formed with a diametral slot 329 enabling axial sliding motion of the blade 324. Slide members 330 and 331, mounted in slideway 329, are provided to prevent this blade from moving otherwise than axially relative to members 322 and 328. Blade 324 extends into an offset core formed by the inner race of a ball bearing 333. This inner race carries, on the radially inner surface thereof, two spur-like elements 334 and 335 which engage the edges 325 and 326 of blade 324 and which project from opposite sides of the race into the diametral slots 323 and 329 of rotary members 322 and 328 whereby this inner race may rotate with the latter. The extent to which this ball bearing 333 is offset in relation to the axis 327 is determined by the axial position of blade 324 and this axial position is governed by a micrometer screw 601 which forms part of the adjustment means hereinafter described. The outer race of the ball bearing 333 is secured to a radial push-rod 336 which is connected, by means of a ball 337 held in a socket 338, to a rocking lever 339 of which one end is pivotally mounted on a pin 340 mounted in the casing of the apparatus and of which the other end carries a tightening clamp 341 in which is held, by means of a knurled-headed screw 342, the lower end of the piston rod 104 of the pump described earlier.

The drive means are thus able both to drive the switching valve 2 in a continuous manner, thereby to place the pump 1 cyclically in communication with the suction tube 11 and with the discharge tube 12, and to drive the eccentric 320 in an intermittent manner, whereby its output member 336, which is connected to pump 11, may have imparted thereto an intermittent reciprocating motion having a freely regulatable amplitude. Wheels 301 and 306 are so keyed in relation to the valve member 203 and to the input shaft 321 of eccentric 320 as to achieve between these various movements the phasing illustrated by the graphs of FIG. 9. In this Figure, curve "Vc" illustrates the operation of the switching valve, curve "Ee" represents the motion of the input shaft 321 of the eccentric and curve "Po" illustrates the operation of the pump. Cycle τ consists, in regard to the valve, of a portion "Asp" during which the pump communicates with the suction tube, portions "C" during which switching occurs and during which communication of any kind is interrupted, and a portion "Exp" during which the pump communicates with the discharge tube (graph "Vc"). As regards the input shaft of the eccentric, cycle τ consists of a portion

" T_1 " during which this shaft rotates through 180° , portions "R" during which it is at rest, and portions " T_2 " during which it completes its revolution (graph "Ee"). As regards the output member of the eccentric, i.e. in regard to the pump, cycle τ consists of a suction phase "Asp" during which the pump carries out a suction stroke, phase phases "P" during which the pump remains stationary, and a phase "Ref" during which the pump discharges the liquid it has sucked in during the "Asp" phase. Pauses "P", during which the pump is idle, overlap portions "C" of the valve operation, i.e. the portions during which switching takes place. Curve "Po" in FIG. 9 further illustrates the sinusoidal nature of the pump's motion, the effect of this sinusoidal motion being progressively to set the liquid in motion and progressively to bring it to rest, thereby avoiding any hydraulic hammering effect. In this graph "Po", there has also been sketched in the extent to which the amplitude of the stroke of piston 102 can be varied, such variation enabling the metering of liquid to be freely varied between a maximum quantity D_{max} and a minimum quantity D_{min} with the possibility of this latter quantity being nil if the axial position of blade 324 is such that the roller bearing 333 is made concentric with axis 327 of the eccentric.

FIRST EMBODIMENT-ADJUSTMENT MEANS

The adjustment means comprise a micrometer screw 601 which cooperates with a nut 602 formed by one of the ends of a stationary element 603 whose other end 604 acts as a bearing for the second rotary member 328 of eccentric 320. Element 603 is kept stationary by a set screw 605 driven into a socket 606 fixed to the rear wall 16 of the apparatus frame. The micrometer screw 601 is formed with a smooth, push-rod forming, portion 607 having a rounded tip which cooperates with the slide member 331 of the eccentricity setting member 324 of the eccentric. Rotation of the screw 601 is controlled by a knurled knob 608, which is rigidly secured to the outside end of a socket 609 which projects out of the casing wall and which, at its inner, open, end, fits over the stationary element 603. Socket 609 carries a sprocket 610 whose function will be explained further on. This sprocket 610 (see FIG. 10) is provided with a pin 611 which projects into a longitudinal groove 612 formed in the outer face of socket 609. In this way, socket 609 can slide axially through the sprocket while remaining angularly stationary with respect thereto. Socket 609 extends also through a setting disc 613 which lies on the outside of sprocket 610 and which is formed with two diametrically opposite recesses 614 and 614'. In these two recesses are movably housed balls 615 and 615' against which act springs 616 and 616'. The function of these balls is to signal to the operator the passage of the groove 612 theretrap. These balls in effect form spring-loaded detents which enable the operator called upon to actuate the knurled adjustment knob 608 to feel when he has rotated screw 601 by half a turn. Setting disc 613 is immobilized by lugs through which extend screws 617 and 618 (see FIGS. 3 and 4) and its function, as will be explained further on, is to set the zero of the display means.

FIRST EMBODIMENT-DISPLAY MEANS

The display means comprise a revolution counter 701 whose input shaft has secured thereto a sprocket 702. This revolution counter is formed with a window 704 (FIG. 4) through which can be seen a set of figures

indicating the number of rotations made by its input shaft. This number is directly related to the rotation carried out by the knurled, eccentricity adjusting, knob 608 and the use of a sprocket chain 703 helps to maintain this relationship by preventing any slip between the sprockets 610 and 702. The diameters of the sprockets 610 and 702, the slope of the edges 325 and 326 on the eccentricity setting blade 324 and the ratio between the arms of lever 339 are so chosen that the volume of the quantity of liquid being metered and discharged can directly be determined by multiplying the number displayed in the window 704 by a calibration figure indicative of the maximum capacity of the pump-acting syringe and which is inscribed on the syringe cylinder.

Further, the ratio between the sprockets 610 and 702 is 2 to 1 so that sprocket 702 will perform one whole turn for every half-turn of the sprocket 610, and hence of the micrometer screw 601. Moreover, the angular position of the setting disc 613 is so chosen that each click made by the spring-loaded detent can cause the number visible in window 704 to vary by one unit. Since the operator will, when making an adjustment, always stop at a click, the number displayed in window 704 is always a full number.

Clearly, the eccentricity of eccentric 320 can only be adjusted by means of the micrometer screw 601 within certain limits; consequently the range within which one can select the quantity of liquid which is to be metered and dispensed by the pump is determined by the maximum capacity of the syringe used to form the pump. Accordingly, in order to increase the range within which this quantity can be chosen, the apparatus is provided with a set of interchangeable syringes having diameters such that their maximum capacities will define a suitably stepped series to form the desired broad range, for example: 0.2; 2; 5; 10; 20; and 50 microliters.

FIRST EMBODIMENT-CONTROL MEANS

The control means comprise the contact-breaker 9 which may, for instance, consist of a microswitch and which is provided with a push-button 20 (FIGS. 4 and 11) actuated by a cam formed by a pair of cavities 21 and 22 in one of the members of the drive mechanism, e.g. in wheel 301 (FIGS. 1, 2 and 4). This switch is connected, as is shown by the electrical wiring diagram of FIG. 11, so as to cut off the motor's supply whenever one of the cavities comes to lie opposite the push-button 20, i.e., twice per revolution of wheel 301. They cause the breaks "R" previously mentioned in connection with FIG. 9. The control means also comprise the automatically cutting out contact-maker 8 which, as can be seen from FIG. 3, includes a contact blade 24 adapted to come into contact with a contact head 25 under the action of a thrust exerted by a push member 26 pneumatically actuated by squeezing a resilient air container 27 adjacent handle 30 (see FIG. 1) and which is connected by a flexible tube 29 to a cylinder 28 wherein the push member 26 is slidably mounted. The contact blade 24 is arranged to lie, at rest, away from the head 25. Between the head of the push member 26 and its cylinder 28 there is provided some play such that the push member will be propelled forward by a sudden increase in pressure brought about by squeezing the air container 27, but such that it will allow the air to leak out so that the pressure of the air is made to drop progressively until it is unable to coun-

teract the elastic force of blade 24. This play is so chosen that the time taken by the contact-maker 8 to open again, through push member 26 being forced back to its position of rest, is enough to enable the motor to rotate wheel 301 by a sufficient angular extent to cause the cavity which had brought about actuation of the contact-breaker 9 to be moved past push-button 20. Since the contact-maker 8 is connected in parallel with contact-breaker 9, the return of 8 to its "open" position will have no effect on the electric supply to the motor. The latter will therefore carry on rotating wheel 301 until the next cavity comes to lie opposite push button 20 to actuate contact-breaker 9. The electrical diagram of FIG. 11 is sufficiently self-explanatory as regards this particular aspect of the operation of the apparatus to make further explanation unnecessary. Attention is however directed to the advantage that such a pneumatically actuated, automatically cutting out, contact-maker has for the operator's safety in view of the risks that are inherent in handling electrical equipment in premises where it would be exposed to splashing by conductive liquids such as water. Since the present metering cum dispensing apparatus is in fact meant to be used in laboratories where such risks do exist, the advantage of this pneumatically actuated contact-maker will be obvious.

This safety feature enables the control means 27 for the contact-maker 8 to be mounted adjacent the handle 30 by means of which the operator holds the nozzle 31 at the end of the discharge conduit 12.

The apparatus hereinbefore described thus provides the following advantages:

Due to the sinusoidal motion of the pump, the liquid can be metered smoothly, the drawing off of a metered quantity and its discharge beginning and ending in progressive manner;

The adjustment of a metered quantity is achieved by means of a micrometer screw and is accordingly highly accurate;

The determination of the volume of a metered quantity is achieved by means of a click system thereby helping to increase the accuracy of a metering operation and its reproducibility; and The volume of a quantity so metered is displayed in numerical form.

SECOND EMBODIMENT

The metering cum dispensing apparatus shown in FIGS. 12 to 16 is, like the first embodiment, dual, inasmuch as it comprises a pair of distributor pumping units 18a and 18b, a pair of drive means 3a and 3b (with however only a single, common, motor 4 and only a single, common, speed-reducing gear), a pair of adjustment means 6a and 6b, a pair of display means 7a and 7b, but only a single control means comprising an electric, automatically cutting out, contact-maker 8 and an electric, cam-operated, contact-breaker 9. Of each of the dual members only one need be described, the components of each such member, except for the distributor pumping units, being identified by three-figure reference numerals so chosen that their first figure corresponds to the reference numeral of the member to which they belong. Thus, all of the components forming part of the drive means, whether they be drive means 3a or drive means 3b, will be identified by numerals ranging from 301 to 399, all of those forming part of the adjustment means, whether they be adjust-

ment means 6a or adjustment means 6b, will be identified by reference numerals ranging from 601 to 699, and so forth. The only exceptions to this rule are the distributor pumping units 18a and 18b whose components will be identified by reference numerals ranging from 100 to 199 (for one part of these components) and from 200 to 299 (for another part of these components). In view of the constructional symmetry of the dual members, the letter symbol that distinguishes one member from the other within a pair will be omitted.

SECOND EMBODIMENT-DISTRIBUTOR PUMPING UNIT

The distributor pumping unit comprises a holder consisting of two tubular casings 130 and 131, fixedly screwed to one another, which enclose a suction and forcing pump and a switching valve, the suction and forcing pump consisting of a syringe made up of a cylinder 132, a plug 133 and of a piston 134 which is provided with a cap 135 and which is mounted at the end of a rod 136, and the switching valve including a stationary valve body 230 and a valve member 231 housed in a rotary socket 232. The holder is provided with a bayonet fitting having studs 151 which engage in slots 152 formed in a Cardan ring 153 which is pivotally mounted, in relation to a fixed portion 154 of the apparatus frame, on a pair of pins (not visible) lying at right angles to the studs 151 and to the plane of the paper. Socket 232, which houses valve member 231, is angularly fixed, by means of a pair of pins 251, with a drive transmission member 252. The top end of transmission member 252 is formed with a crenellated crown 253 defining merlons of triangular shape (saw-toothed). When the distributor pumping unit is in place, the crenellated crown 253 of member 252 cooperates with driving pins 351 forming part of the drive means and a spring-loaded abutment ball 155 exerts an axial force on the center of member 252, this force being transmitted through member 252 and socket 232 to the valve member 231 thereby pressing the latter against the valve body 230 to ensure against leakage. A spring 156 is provided between the transmission member 252 and the socket 232 so as to maintain this tightness when the distributor pumping unit is removed from the apparatus.

The valve body 230 is formed, in its operative face adjacent valve member 231, with central orifice 233 (FIG. 17), which communicates, via an axial passage, with the interior of the syringe cylinder 132, and two lateral orifices 234 and 235 which communicate, via further passages, with conduits 236 and 237. These lateral orifices lie on a circle 238 which is concentric with central orifice 233, and are spaced from one another by an angular distance of 135°. The valve member 231 is formed, in its operative face adjacent valve body 230, with four radially extending linked channels 239 to 242 (FIG. 18) which lie at right angles to one another and which serve to put the central orifice 233 of valve body 230 in communication with either one or the other of the two lateral orifices 234 and 235; in a first condition, that shown in FIG. 18, it is lateral orifice 235 which is made to communicate by the valve member 231 with the central orifice 233 and, in a second condition, which is reached when the valve member 231 has rotated through 45°, it is lateral orifice 234 which is made to communicate with the central orifice.

Consequently, every time valve member 231 rotates through 45°, the valve changes over from one condition to the other. It will thus be observed that with this arrangement of radial linked channels, the valve must be driven in an intermittent manner and is required to rotate through 45° at each step, whereas, in the first embodiment, the valve was driven in a continuous manner, the valve member in this latter case being formed with an anchor-shaped arrangement of linked channels.

SECOND EMBODIMENT-DRIVE MEANS

The drive means comprise a first intermittent drive made up of a driving cogged wheel 301 meshing with a driven cogged wheel 306. This intermittent drive is identical to that in the first embodiment and will therefore not be described again here. Suffice it to say that the teeth of wheel 301 are of reduced axial length along two portions of its periphery so that, during each half turn of wheel 301, wheel 306 also carries out one half turn followed through by a pause which lasts the length of time taken by one set of axially shortened teeth to travel past wheel 306 and during which the teeth of the latter are disengaged from the teeth of wheel 301, and that studs 311 and 311' on wheel 301 and spoke 310 on wheel 306 are provided to facilitate reengagement of the teeth of these two wheels at the end of the above-mentioned pause.

The drive means further comprise a second intermittent drive which is made up of a driving wheel 352 which is mounted on the same shaft as cogged wheel 301 and which carries a diametral spoke 353, and of a driven wheel 354 whose axis lies at right angles to that of driving wheel 352 and coincides with that of valve member 231 in the distributor pumping unit. The driven wheel 354 carries eight radial spokes 355 which are spaced 45° apart, and it is on this driven wheel that are secured the pins 351 that serve to rotate valve member 231. With this arrangement, the driven wheel 354 is rotated by 45° at each half turn of the driving wheel 352 whereupon it becomes completely disengaged from the latter. The position of the radial spokes 355 is so chosen that each rotational step of the intermittently driven wheel 354 will cause the switching valve of the distributor pumping unit to pass from the first to the second of the above-mentioned conditions, then back to the first, and so on, cyclically.

The drive means comprise, moreover, a special eccentric of variable eccentricity. It is special inasmuch as it enables asymmetric variation of its eccentricity. It includes a rotary member 356 rigidly secured to an input shaft 321 on which is keyed the driven wheel 306 of the first intermittent drive. Into this rotary member 356, which is cup-shaped, extends an axially movable crank-pin 357 consisting of a cylindrical rod to one end of which is rigidly secured a cross-piece 358 pivotally mounted on a transversely extending pin 359 carried in blocks slidably mounted in longitudinally extending grooves 360 formed in the rotary member, and to the other end of which is secured a ball 361 housed in an off-center socket 362 formed in an axially slidable, angularly stationary, head 363. The effective length of cross-piece 358 and the position of socket 362 are so chosen that the axis of crank-pin 357 may describe, upon rotation of the rotary member 356, a cone which includes a generatrix that, in its uppermost position lies parallel to the rotational axis of member 356; it is in this, so called "uppermost," position that crank-pin

357 has been shown in FIG. 12. Head 363 is guided, during its axial displacements, by a fixedly mounted sleeve 364 which forms a casing for the eccentric, and a stud 365 which projects into a longitudinal slot 366 formed in casing 364 prevents head 363 from rotating, so that the ball and socket connection 361-362 can only move in a straight line parallel to the rotational axis of member 356, i.e. along the above-mentioned generatrix its uppermost position as shown in FIG. 12.

10 A runner 367 is slidably mounted on the crank-pin 357 and is compelled to move, under the combined action of a transverse slide 368 and of slideways 369 in which slide 368 is mounted, in a plane lying at right angles to the axis of the cone described by the motion of crank-pin 357. Runner 367 therefore describes a circular path which coincides with the intersection of the surface of the cone by the above plane. Since the crank-pin slides in relation to the runner, the diameter of this circle varies, but since the crank-pin lies, in its "uppermost" position, parallel to the axis of its rotational drive, the topmost point of this circle occupies an invariable position. Consequently, any variation of eccentricity brought about by axial displacement of the crank-pin is asymmetrical as opposed to eccentricities 15 20 25 wherein the crank-pin describes a cone having an axis which coincides with the rotational driving axis and having no generatrix lying parallel to this rotational driving axis. In order that the crank-pin 357 may be moved to an axial position such that the apex of the cone comes to be located at the center of runner 367, thereby to cause all motion on the part of runner 367 to cease, ball 361 is off-set in relation to the axis of the crank-pin 357. If it is not necessary for the motion of runner 367 to be caused to cease, ball 361 can of course be centered on the crank-pin axis.

30 35 A yoke 370, of which only a lower portion can be seen in FIG. 12, connects the slide 368, through the intermediary of a hinge 371, to a lever 373 pivotally mounted at one end on a stationary pin 374. There is thus imparted to lever 373 a reciprocating motion having an amplitude which can be made to vary asymmetrically. The opposite, free, end of lever 373 is connected to the piston rod 136 extending out of the distributor pumping unit, by a play-free, readily releasable, coupling which is constructed as follows.

40 45 The lower corner of the free end of lever 373 is cut away at right angles and the vertical face of the resulting notch has driven thereinto a supporting stud 383. In the upper, unnotched, part of the free end of the lever is formed a recess in which is held a ball 384 caused to project by a spring 385, housed in the recess, towards stud 383. As for the piston rod 136, it carries at its free end a slotted socket 157 through which extends a pin 158 having a diameter such that when socket 157 is fitted on to the free end of lever 373, pin 158 comes to be trapped at the bottom of the notch, above stud 383, by the action of the spring-loaded ball 384 which it will have lifted on the way in.

50 55 60 65 The eccentric is provided with an arrangement of spring-loaded detents 375 and 376 mounted on opposite sides of the casing 364 so as to cooperate with a longitudinally extending slot 377 on the outside of rotary member 356. These detents are so positioned in relation to the slot as to be actuated each time crank-pin 357 passes through its "uppermost" and "lowermost" positions. Their purpose will be explained further on.

Head 363 is secured to screw 378, preferably a precision micrometer screw, which cooperates with a nut 379 formed at one end of a tubular casing 372 adapted to be rotated by a knurled knob 380 whereby the axial position of head 363 may be changed by actuating knob 380. In so doing, the amplitude of the reciprocating movement of the eccentric output member formed by yoke 370, and hence the stroke of the pump piston 134, can be varied and the fact that crank-pin 357, in its "uppermost" position, always lies parallel to the rotational drive axis, causes this variation to be asymmetrical, i.e. that the top dead point of piston 134 is always at the same place whatever the length of its stroke. The interest of such asymmetry for stroke variation purposes, by resorting to an eccentric of asymmetrically variable eccentricity, will become apparent later on.

To avoid the difficulties that could arise, as regards accuracy of adjustment, with misalignments of the axes of rotary member 356, of the cylindrical space inside casing 364, and of screw 378, the tubular casing 372 formed with nut 379 is preferably mounted in an elastic bearing, consisting, in the present instance, of three spring wires arranged to form a triangle and engaging more or less tangentially in a groove formed in the periphery of the tubular casing (in FIG. 12 only two of these wires can be seen to wit wires 381 and 382).

As in the first embodiment, the electric motor drives, through a speed-reducing gear 5 and a frictional torque-limiting device 15 (FIG. 8), a single pinion 14 which rotates both driving wheels 301 by meshing with the uncut portions of their teeth.

SECOND EMBODIMENT-ADJUSTMENT MEANS

In addition to the screw 378 and its nut 379, which, in fact, belong to the eccentric, the adjustment means comprise a setting disc 613 (FIG. 20) having balls 615 which cooperate, under the action of springs 616, with a cavity 612 formed in a stepped bush fixed on the tubular casing 372, which disc 613 is secured, once set, to the apparatus frame by washers and screws 617, and the adjustment means further comprise a sprocket 610 secured to the stepped bush by a blocking nut 619.

SECOND EMBODIMENT-DISPLAY MEANS

The display means are the same as those described in relation to the first embodiment, i.e. they include a revolution counter 701 actuated by a chain 703 driven by sprocket 610 (FIG. 1).

SECOND EMBODIMENT-CONTROL MEANS

The control means, which act on the supply of motor 4, comprise, as in the first embodiment, an automatically cutting out contact-maker 8, e.g. one that is pneumatically actuated via a tube 29, and a contact-breaker 9, e.g. a microswitch, actuated by a cam, here consisting of a pair of cavities 21 and 22 formed in driving wheel 301.

SECOND EMBODIMENT-OPERATION OF THE APPARATUS

The setting of the various members that have been described is such that cavities 21 and 22 will actuate contact-breaker 9 when the first intermittent drive (wheels 301 and 306) has caused wheel 306 to become disengaged from the driving wheel 301; diametrical spoke 353 has not yet come into engagement with a radial arm 355 when contact-breaker 9 has cut off the

supply of motor 4; and slot 377 is in engagement with one of the spring-loaded detents 375 and 376 when contact-breaker 9 causes motor 4 to stop; the crank-pin 357 of the eccentric is then accurately immobilized in its "lowermost" position or in its "uppermost" position and the same applies to piston 134.

This being so, the automatically cutting out contact-maker 8 can be actuated to supply electric current to the motor 4 which is thus set in motion. Cavity 21 (or 10 22 as the case may be) is caused to move past the push-button of contact-breaker 9, thereby depressing, the push-button to render the contact-breaker inoperative to close the motor circuit. Thus, upon contact-maker 8 automatically returning to its inoperative position 15 after a predetermined lapse of time, the resulting cut-out will by then have no effect on the motor which continues to rotate. The second intermittent drive, through its diametrical spoke 353 acting on a radial arm 355, causes, at the same time, valve member 231 to be angularly moved thereby causing it to pass from one of its 20 two conditions to the other (portion C of each half-cycle A, curve Vc, FIG. 19). At that point in time, the first intermittent drive comes into action and starts to drive rotary member 356 of the eccentric (end of pause 25 P of each half-cycle A, curve Ee, FIG. 19). When this member has turned through 180°, i.e. when driving wheel 301 has completed half a turn, cavity 22 causes the contact-breaker 8 to become operative and motor 4 stops. During the half-turn of rotary member 356, piston 134 will have completed one stroke ("Asp" or "Ref", curve Po, FIG. 19). These movements together constitute half an operational cycle, such a half-cycle either being a drawing off half-cycle (if the pump has performed a suction stroke, i.e. if piston 134 has moved downwardly), or being a discharging half-cycle (if the pump has performed a forcing stroke, i.e. if the piston 134 has moved upwardly). The operator can then take whatever time he needs to change the containers into which dip the ends of conduits 236 and 237 and once this is done he can then trigger off, by means of contact-maker 8, the next half-cycle (interruption "Int", FIG. 19).

It will thus be observed that this second embodiment, constructed as has just been described, operates in much the same way as the first embodiment; it has, however, in relation to the latter the following distinctive features:

50 The pump and the valve, through being grouped together to form a distributor pumping unit which can readily be removed without any form of dismantling, can easily be exchanged (for instance to alter the range within which the volume of a metered quantity can be varied by resorting to a syringe of different maximum capacity);
 55 The separate sterilization of the pump and of the valve, involving subsequent reassembly under sterile conditions, can be replaced by sterilization of the distributor pumping unit as a whole (including even, conduits 236 and 237);
 60 Since each half-cycle starts off with the actuation of the valve there is no need to take any particular steps, when putting the distributor pumping unit back in place, to set the valve member in the correct position as this will be done automatically, and the saw-toothed outline of the crenellated crown 253 helps to achieve smooth interengagement of the teeth and the driving pins 351;

The valve can readily be moved by the operator from one of its operative conditions to the other by acting on the radial arms that project from the front portion 154 of the apparatus frame: this possibility enables the roles assigned to conduits 236 and 237 to be reversed, so that either can selectively be used for drawing off liquid or for discharging liquid; Any change in volume of a metered quantity by rotating knurled knob 380 (which, by changing the axial position of crankpin 357 causes the eccentricity of the eccentric, and hence the stroke of piston 134, to be varied) does not cause the piston to move at all when the crank-pin lies in its "uppermost" position, and hence does not cause any movement of liquid in the conduits; this is an important advantage afforded by the use of an eccentric of asymmetrically variable eccentricity.

IMPROVED METERING AND DISPENSING APPARATUS

The apparatus shown and generally designated as 900 is an improved version of the two piston, sinusoidal stroke metering and dispensing apparatus.

It consists generally of a base member 901 having support pads 902, 903. A rear support plate 904 extends upwardly therefrom and has a circular aperture 905 therein for accomodating a reduced diameter portion of the tubular housing 401 of a stroke adjusting mechanism 400. A support plate 800 extends upwardly from the base plate 901 and is parallel to a face plate 837 extending upwardly from the front of base plate 901. Lateral support members 937 and 938 support the various members in conjunction with L-shaped brackets 938'. Support plate 800 has a circular aperture therein corresponding to aperture 905 in plate 904 for receiving a reduced diameter portion of housing 401 of mechanism 400.

Members 919, 920 support a gear box 918. A support member 916 is attached thereto and supports a motor 915 which is connected to the gear box 918 by drive shaft 917. Gear box 918 contains reduction gears which are connected to a pinion drive shaft 921 which, through a coupling member 922 drives a pinion stud and pinion gear 806. Pinion gear 806 drives idler gears 807, 808 which are mounted for rotation on plate 800 by screws 929 and sleeves 928. Microswitches 923, 925 are mounted between plate 800 and the rear face of gears 807, 808. They can be activated by arcuate detents (not shown) in the rear face of gears 807, 808 acting in cooperation with spring-loaded contact members (not shown) to control the timing and operation of the device; in lieu of the contact members and detents, small insert magnets 926 may be inserted in the rear face of gears 807, 808 to activate the microswitches.

Mounted on the front of face plate 837 is valve switching mechanism 502 with pump members 500 depending therefrom.

At the rear of motor 915 is mounted a fan 935 having blades 936. Fan 935 is mounted to motor 915 by shaft 934. The fan 935 is operated only when motor 915 is on by the attraction of the electromagnetic field of the motor attracting plate 933 pivoted to member 930. Plate 933 is maintained in position by spring 933'. A member 931 supports this mechanism. The contact of plate 933 with the motor 915 completes a circuit to set the fan running.

On the rear of plate 904 is an adjustment knob 909 and shaft 908 for setting the length of the piston stroke. Knob 909 is mounted for rotation within a sleeve 907 which is adapted to rotate with the shaft 908. A wheel 910 is mounted for rotation with sleeve 907. Through an endless link drive 913, wheel 910, upon rotation of knob 909, moves drive 913, which, in turn, rotates wheel 912 connected to a counter 911 mounted on a support 906. A window 911' is located on top of counter 911 for viewing the number therein, which is usually from 0-100. The zero reading corresponds to zero stroke length and 100 corresponds to maximum stroke.

Of course, the counter 911 is illustrated as adjacent the top of plate 904 only for purposes of illustration, it being understood that it may be located in the front of the metering and dispensing apparatus or in any location.

STROKE ADJUSTMENT MECHANISM

The device previously referred to is generally designated by 400 in FIG. 23. It is housed in a cylindrical casing 401 having annular internal grooves 402 at one end to receive snap rings 430. The opposite end has an annular internal groove 403 which is adapted to receive a snap ring 407. A tubular member 404 is mounted for rotary movement within casing 401 on bearing surfaces 405 and is prevented from sliding longitudinally within 401 by rings 407 and 407'.

There are two parallel juxtaposed longitudinal slots or slideways 406 in the inner surface of member 404.

A solid cylindrical member 408 is mounted for longitudinal sliding movement within the casing. It is prevented from rotating relative to the casing by a screw 410 carrying a rider and 411 threaded into a hole 409. Rider 411 cooperates with a slot 412.

A cylindrical bore 413 located in member 408 receives a hollow cylindrical insert 414, press fitted therein or screwed therein. The internal diameter of insert 414 is pinched as at 415. A flange 416 maintains the insert 414 against sliding movement within member 408. A jeweled ball 417 is received in the end portion of insert 414 and is maintained there by a spring 419 pushing against a member 418. A screw-threaded stud 420 keeps the spring in compression within the insert member.

A coaxial bore 423 receives the end portion 422 of a threaded rod 421. Portion 422 is either press-fitted into bore 423 or fastened therein for non-rotative movement. An internally-threaded sleeve 424 engages a reduced diameter threaded portion 425 and a portion of the larger diameter section of 421. In the position shown in FIG. 23, the stroke would be adjusted to an intermediate length between zero and its maximum length. Sleeve 425 is mounted in a spherical portion 428 of a bearing having its outer race 429 between rings 430. The end of portion 425 has a slot 426 therein and a pin 426. Slot 427 and pin 427 are adapted to cooperate with sleeve 907 and shaft 908 which is inserted into slot 426 and retained therein by pin 427. By turning sleeve 424, rod 421 moves longitudinally in either direction, depending on the direction of rotation.

Ball 417 receives an extension member 432 of a crankpin 431. The extension member 432 is offset from the axis of pin 431. Referring now to FIGS., 23 and 25, crank-pin 431 is connected to a swivel member 432a

having swivel studs 433. Member 432a is mounted in bearing member 434 in rectangular cutout portion 435 and swivels therein on studs 433 which are received in holes 437. Member 434 has the general shape of a semicircle but its arcuate periphery extends over 180° for a reason to be explained. The outer circumference of member 432 has an arcuate raised portion 438 which is relieved as at 439 to accommodate the end of studs 433.

Member 434 is received within a slide member 440 which is generally rectangular with opposite parallel slide surfaces 443, 444. Member 440 has a generally semi-circular cut-out portion 441 which is slightly larger than a semi-circle or 180°. An annular groove 442 extends around the arcuate edge of the cut-out portion and is adapted to receive raised portion 438 of member 440. The reason that member 434 and cut-out portion 441 of member 440 are slightly larger than a 180° semi-circle is to allow member 434, usually made of steel or a like metal, to snap into member 440, usually made of bronze or like material.

The surfaces 443, 444 of member 440 are adapted to slide in longitudinal slots 406 of member 404.

Crank pin 431 is mounted for sliding movement within the central portion of a spherical bearing 445, the outer race 446 of which is grooved as at 447 to slidably fit between rods 448, 449. Rods 448 and 449 are fixed to cross pieces 450 and 451, respectively. Rod 448 extends through the cross pieces in order to hingedly accommodate arms 454 and 455 of member 456, shaped like a tuning fork. In FIG. 24, it is seen that member 456 has a lower depending portion 457 which has a rectangular aperture through which extends stroke bar 460. A set screw 458 in bore 457 of member 456 maintains the relationship between bar 460 and member 456.

Bar 460 is mounted for rotative movement on pin 461 which is mounted in mounting block 462 in cut-out portion 463. Block 462 has a recessed area 464 which receives a machine screw 465. Screw 465 passes through a bore in the block and is threadedly engaged in threaded bore 467 in the base of casing 401. An insert 466 spaces block 462 from the casing 401.

At the forward end of rod 460 is a small diameter bore 467 for receiving shaft 585 adapted to transmit the stroke to piston 500. A bore 468 receives set screw 587 for retaining shaft 585 in the end of bar 460.

Mounted on the extending portion of member 404 is a gear 470. Gear 470 has teeth 472 and a circular slot which receives the end 471 of member 404. Gear 470 also has reduced diameter portions 473 and 474 which receive a cap member 475. Gear 470 and cap member 475 have the same diameter bores, 479 and 478, respectively. A set screw 480 secures cap member 475 to reduced diameter portion 474.

Crank pin 431 describes a cone in its rotation and is parallel to the axis of rotation of member 404 when at the top of its rotation position. To adjust the arc through which bar 460 moves, sleeve 424 which is fixed in its longitudinal movement is turned on its axis. Turning sleeve 424 moves rod 421 longitudinally in either direction thus shortening or increasing the distance through which cross pieces 450 and 451 move. The arcuate movement of the end of bar 460 is sinusoidal due to the nature of the kinematic arrangement of the mechanism. The bar 460 is prevented from chattering or bouncing due to looseness or play

by a constant force coil spring 483, shown in FIG. 24, one end of which is coiled about the bar as at 485 and the other end of which is bent, as at 484, and is received within a slot 482 in casing 401.

5 The device can be used to provide sinusoidal movement to any other device, such as a piston and cylinder. It is an improvement over straight reciprocal, linear movement which tends to start off quickly and diminish quickly. In the movement provided by the instant device, the maximum speed of movement occurs in the middle of the travel distance with acceleration and deceleration phases before and after this point of maximum speed.

And, more importantly, the length of travel, whether 10 arcuate or linear can be linearly adjusted either before or during the movement of the device with a great degree of accuracy.

PUMP AND VALVE ARRANGEMENT

A preferred embodiment of the distributor pump is 15 designated generally as 500. While two pumps are employed only one is described, it being understood that the pumps are identical except that the capacities may be varied. The lower surface of stationary supporting member 502 has a longitudinal groove 504 therein for a purpose to be described. Member 502 has holes 503 (to facilitate mounting of number 502 on supports 800 and 837) and a cut-out area or recess 505 for accommodating cylindrical pump housing 501. 20 As seen in FIG. 28, member 502 extends laterally away from cylinder 501, the purpose being to accommodate another cylinder. A bore 506 extends vertically from area 505 up into member 502. A lateral tapered bore 507 intersects bore 506. A sleeve 508 and a washer 509 pivotally mount a valve actuating lever 510. Lever 510, referring now to FIG. 27a is an elongated member having a projection 511 for actuation by the pump valve actuating mechanism 800 (FIGS. 21 and 26). Sleeve 508 passes through a 25 figure-eight type slot 513. The slot is made in this configuration so that the member 510 may pivot in either end of the slot about sleeve 508. The purpose of this arrangement is to allow an operator to pull on tab portion 512 of the member to slide the member forwards, thus disengaging projection 511 from valve-actuating assembly on support 800. When one 30 pushes on tab 512, the pivot point of member 510 re-engages the actuating assembly due to the change in 35 pivot axis.

Member 510 also has valve-stud driving slots 514 and 40 515. A shaft 516 extends into bore 506 and has a relieved section 517 to accommodate a tapered locking pin 518. Locking pin 518 has a flattened tab portion 519 by which an operator may insert it into member 502.

The other end of shaft 516 terminates in a jewel bearing 520 which is held in a recess 522 of circular member 521. A flat plate member 523 having a central aperture therein for accommodating shaft 516 is secured to circular member 521 by a set screw 524 and is rigidly attached to upper end of cylinder 501.

Member 521 is located in a circular aperture in rotary plug member 525 having valve-driving studs 526, 527 located thereon. The top of cylinder 501 is open and studs 526, 527 engage in driving slots 514, 515, respectively, of member 510.

Member 525 is attached to rotary valve member

532 and a spring (528)-pressed bearing plate 531 by pin 533. When member 510 is driven reciprocally, the motion is translated to the valve member 532 to implement switching of the ports.

Member 501 does not rotate due to the action of slot 504 on pins 529, 530 which are rigidly attached in any suitable manner to the member 501. These pins limit the degree of entrance of member 501 in recess 505.

As shown in FIGS. 27 and 28, the pump 500 could swivel as a unit about the spherical bearing 520 except for the pin means 529 and 530 which restrict such motion to a swinging about the axis of the pin means which is at right angles to the plane in which shaft 585 reciprocates. The pin means also prevents the lever 510 from rotating the pump unit about its axis when the rotary valve member 532 is reciprocated about its axis.

A spring 528 biases member 521 upwards and, through plate 521, it presses the lower face of valve member 532 against the upper face of stationary block 534, thus providing, by virtue of the rigid attachment of 521 to the upper rim of housing 501, a swivel connection on ball bearing 520.

The valve arrangement is shown in FIG. 29. The lower face of member 532 has a central aperture 539 connected with radially extending channels 540 and 541. The ends of these channels are adapted to alternately and respectively overlie port bores 542 and 543 (as shown in FIG. 30) in stationary block 534. Block 534 is fixed to a casing 535 by pins 537 in bores 536 extending through 535 and also into block 534 and has a central bore 538 in communication with aperture 539 in valve member 532. Port bores 543 and 542 are in communication with ports 544 and 545, respectively, which protrude out from casing 535 through a cut-away section 546 of member 501. Section 546, as seen in FIG. 28, has a notched cut-out portion 547 at the top thereof and has snap rings 536 holding pins 537 in place.

Thus it is seen that upon reciprocal rotation of member 532, the bore 538 is alternately in communication with port 544 and port 545.

A circular coaxial recess 548 in the lower face of block member 534 receives the end of a tubular glass cylinder 549. The opposite end of cylinder 549 is received in a like recess 551 in bleed block 550. Gaskets, such as 548' seal the ends of glass cylinder 549 into the recesses 548 and 551.

Bleed block member 550 is generally cylindrical in configuration and has a central bore therein receiving positive displacement piston 552 of constant diameter.

A manually operated bleed and priming knob 553 extends from the front of cylinder 501 through a cut-out portion 560 therein. Knob 553 has a circular bore therein which receives a priming port member 557. Port member 557 has a large diameter bore 554 tapering into a small diameter bore 555. Knob 553 and port member 557 are fixed for rotation together by pin 556 and knob 553 has external threads 558 which engage a threaded circular insert member 559 in area 560 of member 550.

A channel and bore 563 extend down and out from the area enclosed by glass cylinder 549 and are in communication with the relieved area 560 in block member 550. A circular-shaped sealing projection 562 keeps the end of port member 557 away from the end surface of the relieved area 560, and breaks the communica-

tion between bores 555 and 563. A sealing ring 561 is located in an outer annular groove in port member 557 to prevent any leakage from occurring.

As knob 553 is rotated, the circular-shaped projection moves out of engagement with the end wall of the cut-out area 560 and bore 555 is in open communication with bore 563. The purpose of this arrangement is to allow a small-volume piston and cylinder combination (the cylinder and pistons may vary in size) to be primed. Large-volume piston and cylinder combinations in some cases provide enough suction on the intake stroke so as to be essentially self-priming.

In the instances where the pump has to be primed, a hypodermic syringe (without the cannula) is inserted into the large diameter bore section 554 of the port 557 to provide suction within glass cylinder 549.

A washer 566a is positioned directly beneath member 550 and it and member 550 are held in place by an externally threaded insert member 567. The threads of insert member 567 engage internal threads 568 in the end of member 501 to hold the components of member 501 in place.

Insert 567 has internal threads 569 which are engaged by threads 571 of an adjustment member 570. Adjustment member 570, as shown in FIG. 27, has a central bore 573 through which passes piston 552. A reduced cylindrical portion 572 of adjustment member 570 abuts a washer 565 located at the base of a large bore 564 in the base of member 550. Between the washer and the end wall of the bore are V-shaped compression seals 566, their purpose being to prevent any leakage between the piston 552 and its bore in member 550. By turning adjustment member 570, provided with a roughened or serrated knob portion 574, compression is brought to bear on the seals 566. A guide sleeve 575 is located between adjustment member 570 and piston 552.

The end of piston 552 has a reduced diameter threaded portion 578 which is received within a threaded bore 577 in support member 576. Surrounding member 576 and attached thereto by screw 581 engaging internally-threaded bore 582 is a resilient clip 579. The body of clip 579 is C-shaped and snaps onto support member 576 as shown in FIG. 27. An L-shaped resilient projection 580 extends downwardly from the clip body and cooperates with a relieved area 583 to maintain a jewel bearing 584 or any other suitable type of bearing. Bearing 584 is fixed on the end of the rod or shaft 585 which, in turn, is received within a bore of crank arm 460. A set screw maintains shaft 585 in position. It is understood, of course, that any type of connection between piston 552 and reciprocating arm 460 may be used.

VALVE SWITCHING MECHANISM

Referring to FIG. 26 there is shown the driving arrangement for the eccentric stroke mechanism 400 and the valve switching mechanism. Mounted on support plate 800 are spacers 801, 802 aligned with mounting holes 803 to mount block 502 to face plate 837 which in turn is secured by bolts (not shown) and spacers 801, 802 to plate 800.

The bottom edge of plate 800 has two cut-outs as indicated by numeral 805 to allow the end of arm 460 to protrude therethrough. A pinion gear 806 is positioned approximately on the center line of the plate 800 and drives two idler gears 807 and 808. Gears 807 and 808

are identical and it is to be understood that the description of gear 807 applies equally as well to gear 808.

Gear 807 has teeth 808' therearound except in two relieved areas 809 and 810. Studs 811, 812 are mounted on the side of gear 807 for a purpose to be described. A raised reduced diameter member 813 forms a base for a cam 814 which are both mounted on a stud 815. Both member 813 and cam 814 may be either separate members or may be made an integral part of gear 807.

Mounted below and in engagement with the forward edge of gear 807 is drive gear 470. It is understood that an identical gear resides under idler gear 808 and that the description of gear 470 applies to said other drive gear. Drive gear 470, as previously described, has a cap member 475 attached thereto with protruding spokes 476, 477. Spokes 476, 477 are engaged by pins 811, 812 on gear 807 when gear 470 is out of engagement with teeth 808' of gear 807. I.e., the two relieved areas 809, 810 on gear 807 are to provide a pause between the intake and discharge strokes of the pistons. The purpose of spokes 476, 477 and pins 811, 812 is to start gear 470 moving before teeth 808' engage the teeth of gear 470 to insure a proper meshing of the teeth.

Adapted to be mounted over and ride on the surfaces of cam 814 and its counterpart on gear 808 is guide member 817. Generally, guide member 817 is a plate with two apertures 823 and 824. Aperture 824 has parallel internal edges 825, 826 and offset parallel edges 827, 828 and vertical end edge 829. Aperture 823 has an identical configuration. Both apertures cooperate with cam 814 and cam surface 816 to provide a vertically reciprocal movement to member 817 in a manner to be described. Member 817 has a depending portion 819 having a vertical notch 821 therein and two projecting studs 820, 820'. A second vertical notch 822 is provided in the upper edge of member 817 and is aligned with notch 821. A circular aperture 818 is located between apertures 823 and 824.

Mounted on member 817 for reciprocal pivotal movement are pivot plates 830 and 831, it being understood that the plates are symmetrically identical. Plate 830 has a projecting portion 832 with a hole 833 therein. The top of plate 830 has an arcuate edge 835 with a centrally located notch 836.

Hole 833 is adapted to receive stud 820 so that pivot plate 830 may be mouted to overlie aperture 824. Plate 830 has a central aperture 834 therein to accommodate the end of stud 814 which prevents it from pivoting 180° to a downward position. The shape of aperture 834 also limits the extent of reciprocal travel of plate 830.

To prevent member 817 from moving laterally, studs 843 and 844 are provided on the inner side of face plate 837. These mate with notches 821 and 822 which allow member 817 to move vertically in a reciprocal fashion.

Face plate 837 has mounting holes 838 which, when aligned with spacers 801, 802, and holes 803 in plate 800 accommodate bolts (not shown) which also pass through holes 503 in member 502. Vertical slots 841, 842 are located in the base of face plate 837 and allow shafts 585, mounted in arms 460 to reciprocate therein.

Member 502, previously described, mounts on the top front of face plate 837 and the projections 511 of pivot members 510 pass through horizontal slots 839

and 840 in plate 837 and reside in notches 836 in plates 830 and 831.

The operation of the valve switching mechanism is as follows. With valve member 532 in one position in cylinder 501, idle gears 807, 808 drive drive gears 470 to, e.g., move arm 460 downwardly, which retracts piston 552 for an intake stroke. Due to the shape of apertures 823, 824, no substantial vertical movement of member 817 occurs.

- 10 When the intake stroke is completed, gear 807 disengages gear 470 due to the position of one of the relieved areas 809, 810 and the stroke drive and adjustment mechanism 400 ceases to move arm 460. During the period in which gear 470 is not driven, however, the action of cams 814 on the edges of apertures 823, 824 drives the member 817 in a downward direction. Because plates 830, 831 are loosely pivoted about stud 815, the downward movement of member 817, through the stud 820 connection with hole 833 in pivot plate 830, the edge 835 of plate 830 moves arcuately laterally thus turning pivot member 510 due to the notch 836 engaging the projection 511. The pivoting of member 510 rotates the valve 532 so that another port is connected with bore 538 leading into the cylinder 549.
- 15 The shape of apertures 823, 824 then provides for the cam 814 to rotate without any change in the position of member 817. At the same time, one of the spokes 476, 477 engage either pin 811 or 812 and start gear 470 to moving. Rotation of gear 470 then initiates the
- 20 upward movement of arm 460 and the discharge stroke begins. The liquid, however, is discharged through a different port from which it entered.
- 25

If it is desired that the valve remain in one position, i.e., the intake and discharge occur through the same port, one simply pulls on tab 512 of either or both of the members 510 which disengages the projection 511 from being driven by notch 836.

- 30
  - 35
  - 40
  - 45
- The power operation for the apparatus may be set by microswitches such as 923, 925. The timing may be set up similar to that described in the first two embodiments with a remote control actuating switch, e.g., like a shutter control on a camera.

Another improved feature of this invention is that the pistons can be driven in parallel, alternately or with overlapping strokes. This can be accomplished by changing the relationship of the gears 806, 807, 808 and 470. I.e., the pinion gear, as shown in FIG. 26, is disengaged and the idler gear 808 and its accompanying drive gear are rotated to a new position and the gear 806 is re-engaged.

USES OF THE APPARATUS

FIGS. 31 to 34 illustrate the various systems that can be set up with the device, using any one of the three embodiments.

Referring to FIG. 31, the apparatus is shown used as a sample diluter. One of the valves is fixed in position so that the intake and discharge stroke operate on the same port. The two pistons work in parallel. In the first movement of sample (dark fluid) is aspirated by the piston with the fixed valve into the delivery tip and the rinsing and/or reagent solution (light fluid) is aspired by the other piston. In a discharge stroke, the aspirated solution and the sample are delivered simultaneously by the tip.

In FIG. 32, the device is used as a double dispenser. The pistons again work in parallel and a first solution

(dark liquid) and a second solution (light liquid) are aspirated in the pistons respectively on the intake stroke and then delivered simultaneously into the test tube through the delivery tip. More than one delivery tip can be used.

In FIG. 33 the apparatus is shown employed as a double speed single dispenser. The two pistons, set at the same volume are arranged to act alternately and deliver in an alternating manner one solution (dark liquid).

The use of the apparatus as a distributor of undiluted samples is shown in FIG. 34. The pistons, set at the same volume, are arranged to overlap their intake and discharge strokes so that when one piston is finishing its discharge stroke the other has begun to aspire solution from the supply. However, during this aspiration, solution is being dispensed because of the location of the dispensing tip between the reservoir and the piston on its intake stroke. This produces a siphon effect and solution is dispensed. This piston then discharges its intake but into the supply. The apparatus then acts at the speed of the system shown in FIG. 33.

Thus, it is seen that the subject matter of this invention provides an improved accurate metering and dispensing apparatus capable of many uses.

While only three embodiments of the metering and dispensing apparatus have been shown and described, it is apparent that many changes and modifications will occur to those of ordinary skill in the art within the scope of the appended claims.

What is claimed is:

1. A measuring and dispensing apparatus comprising a base, motor means, a first motion-translating means adapted to translate rotary motion into sinusoidal reciprocal motion, a second motion-translating means adapted to translate rotary motion into substantially reciprocal movement, power-translating means connecting said motor means and said first and second motion-translating means to operate them a pump having a cylinder and a piston reciprocable in the cylinder, valve means having a passage communicating with the interior chamber of the cylinder and two ports and adapted to alternately connect each of said ports with said passage, a support member on said base, means for connecting said pump to said member, said second motion-translating means being operatively associated with said valve means and operating it to alternately connect each of the ports with the chamber through said passage at set times, and a reciprocating arm connected to said first motion-translating means and said piston to provide strokes of sinusoidal amplitude thereto.

2. An apparatus as in claim 1 wherein the cylinder and valve means are mounted within an elongated tubular housing, the valve means being adjacent an end wall of the cylinder and comprising a rotary member having a passageway adapted, on reciprocation of the rotary member about its axis, to alternately place each port in open communication with the chamber through the aforesaid passage, at least one driving stud secured to the rotary member and projecting beyond said end of the housing, the valve-switching means comprising a reciprocable valve-driving means, and lever means engaging the stud or studs and arranged to be reciprocated by the reciprocable valve-driving means for reciprocating the rotary member about its axis.

3. An apparatus as in claim 2 wherein the pump-connecting means comprises a second stationary supporting member having a bore and a groove therein, a shaft having a spherical bearing on which the housing and the valve means are supported for relative motion, said shaft extending into said bore, means for locking said shaft in said bore, a sleeve surrounding a portion of said shaft and supporting said lever means pivotally thereon, and pin means rigidly attached to the housing and projecting axially therefrom, the pin means having an axis at right angles to the plane of reciprocation of the arm and engaging the slot and being rotatable therein to permit swinging of the housing on the axis of the pin means while preventing rotation of the housing about the axis of the rotary member during reciprocation of the lever means to actuate the valve.

4. The apparatus as in claim 2 wherein said lever means has at least one slot therein engaging said driving stud, and a projection on the end of said lever engaging said second motion translating means.

5. The apparatus of claim 4 wherein said lever has a figure eight shaped slot, said shaft engaging said lever through said slot whereby said lever can be moved longitudinally to disengage said lever projection from the second motion translating means to leave the cylinder chamber means in communication with only one port bore or neither.

6. An apparatus as in claim 1 wherein said pump includes a priming means, said priming means adapted to place a source of suction in open communication with said cylinder means.

7. An apparatus as in claim 8 wherein said priming means comprises a manually operable rotatable threaded valve member, a threaded aperture in said housing, a first passage means in said valve member, a second passage connecting said valve member with said cylinder, said valve member having a gate means adapted to place said first and second passage means in open communication upon rotation of said valve means.

8. An apparatus as in claim 2 wherein said power transmitting means includes at least one driven gear, a cam mounted on said gear, a plate means mounted for vertical sliding movement on said base means, an aperture means in said plate means, said aperture means surrounding said cam means and adapted to vertically reciprocate on said cam means, said aperture means being so configurated that said plate means pauses between its upward and downward movements, at least one pivot plate member mounted for pivotal movement on said plate, a second smaller aperture means located on said pivot plate member, a stud on said cam projecting through said second aperture means and adapted to limit the amount of pivotal movement of said pivot plate member, a slot in said pivot member, said lever means having a projection engaged in said slot whereby the rotation of said gear rotates said cam, thereby causing said plate means to intermittently vertically reciprocate which, in turn, causes the pivot plate member means to reciprocally pivot within the limit prescribed by said stud upon upward and downward movement of said plate, and the movement of said pivot plate member actuating said lever means.

9. An apparatus as in claim 8 wherein the first aperture means comprises the shape formed by two overlapping rectangles.

10. An apparatus as in claim 8 wherein said first motion translating means has a second gear driven by the first-mentioned gear, said first and second gears engaged to drive said first motion translating means, said first gear having two arcuate relieved portions on its circumference whereby said second gear is intermittently driven upon rotation of said first gear, the times when said second gear is not driven corresponding to the up and down movements of said plate means to allow said valve switching mechanism to change ports on said pump.

11. An apparatus as in claim 10 wherein said first gear has two upstanding studs adjacent said relieved portions and said second gear has two spokes projecting from a hub portion thereof, said studs engaging said spokes respectively to start said second gear rotating before the gears remesh.

12. An apparatus as in claim 8 wherein said first motion translating means includes means to linearly adjust the length of stroke of said reciprocating arm.

13. An apparatus as in claim 8 wherein said cam, plate means and pivot plate member are located between the first-mentioned support member and another support member upstanding portions of said base.

14. An apparatus as in claim 1 wherein said power transmitting means includes a reduction gear box, said reduction box is connected to said motor, at least one idler gear is driven by said reduction gear box, and a gear for driving said first motion translating means is in engagement with said idler gear.

15. An apparatus as in claim 14 wherein said base has microswitches mounted thereon adjacent said

idler gear, and there is means on said idler gear adapted to activate said microswitches to control the operation of the apparatus.

16. An apparatus as in claim 14 wherein said idler gear has means thereon to activate said second motion translating means.

17. An apparatus as in claim 16 wherein said activation means comprises a cam.

18. A system for metering and dispensing liquids comprising at least two pumps, each pump having a piston and cylinder and at least two ports thereon, power means to drive said pistons, a reservoir means, adjustment means adapted to adjust the stroke on each piston, manually adjustable valve means on each pump adapted to connect said pump cylinders with either both ports alternately or only one port, a common dispensing and aspirating nozzle in communication with one port on each pump, said reservoir being in communication with at least one of the other ports of the two pumps, each pump including interchangeable members, thereby allowing the capacity of the pumps to be varied, whereby said arrangement allows for many dilution and sampling procedures to be carried out on said system.

19. A system as in claim 18 wherein said power means driving said pistons may be adjusted so that the pistons move in parallel or alternating strokes.

20. A system as in claim 18 wherein said power means includes cam means adapted to only operate said valve means when said pistons are at the top or bottom of their strokes.

UNITED STATES PATENT OFFICE
CERTIFICATE OF CORRECTION

Patent No. 3,780,912 Dated December 25, 1973

Inventor(s) Manuel Claude Sanz

It is certified that error appears in the above-identified patent and that said Letters Patent are hereby corrected as shown below:

Col. 7, line 7, "phause" should be --pause--.

Col. 14, line 12, "inoperative" should read --inoperative, i.e.--.

Col. 16, line 36, "and 411" should read --411 and--.

Col. 17, line 7, "432" should read --43⁴--.

Col. 17, line 7, correct spelling of "arcuate".

Col. 18, line 38, "mechanism 800" should read --mechanism on support 800--.

Col. 23, line 37, "power-translating" should read --power-transmitting--.

Col. 23, line 39, a comma (,) should be inserted after "them".

Col. 24, line 33, "8" should read --6--.

Col. 25, line 24, "portions of" should read --from--.

Col. 26, lines 29 and 30, "to only operate said valve means when" should read --to operate said valve means only when--.

Signed and sealed this 1st day of October 1974.
